UNITED STATES PATENT OFFICE

2,583,446

FLOOR WAXING DEVICE

Charles M. Sinnard, Grand Island, Nebr.

Application June 8, 1948, Serial No. 31,648

1 Claim. (Cl. 91—39)

1

This invention relates to a combined push broom, dust mop and floor polisher.

It is an object of the present invention to provide an attachment for a broom handle adapted for applying floor wax to the floor for the purpose of being spread thereover and to polish the floor and wherein the attachment upon being removed will leave the broom free for its ordinary use, the attachment having a mop extending therefrom so that without the use of the wax the attachment can be used as a mop, a handle portion extending from the attachment for the use of the same free of the broom handle.

Other objects of the present invention are to provide a combined mop, broom and floor polishing arrangement which is of simple construction, easy to assemble, inexpensive to manufacture and efficient in operation.

For other objects and for a better understanding of the invention, reference may be had to the following detailed description taken in connection with the accompanying drawing, in which

Fig. 1 is a sectional view, in elevation, taken through a broom and through the floor polishing and mop unit.

Fig. 2 is a top plan view of the broom and mop unit assembled as shown in Fig. 1.

Fig. 3 is a transverse sectional view taken on line 3—3 of Fig. 1.

Fig. 4 is a longitudinal sectional view taken on line 4—4 of Fig. 1.

Fig. 5 is a fragmentary view looking upon the brush and upon the attaching plate thereof.

Fig. 6 is an elevational view of the mounting bracket for the floor polishing attachment.

Fig. 7 is a fragmentary elevational view of the floor polishing attachment.

Fig. 8 is a side elevational view of the brush with the attachment removed from the same.

Fig. 9 is a side elevational view of the attachment separate from the broom and with a handle extended into its retainer for the use of the attachment free of the broom and as a polisher or as a mop.

Referring now to the figures, 15 represents a broom having bristles 16 and a handle 17 extending upwardly therefrom. To the rear side of the main body of the broom 15 two plates 18 are secured by screws 19. Stud bolts 21 carried by the plates 18 and thumb nuts 22 thereon, provide means for securing a connecting member or bracket 23 of U-shape to the brush body. The member or bracket 23 extends rear-

2

wardly from the brush body. A combined mop and floor polishing attachment 24 is attached by means of bolts and thumb nuts 26 to the rear end of the bracket 23. The member 23 has a bracket portion which extends upwardly and which has a sleeve formation 27 through which handle 17 extends.

The attachment 24 includes a bottom member 31 adapted to be extended against a flange 32 of a casing 33 for the securement of mop trailings 34 thereto. A plate 35 extends over the member 31 and has a trough 350 which extends through its longitudinal center and is provided with central holes 36 extending throughout the length of the trough and the trough is adapted to receive wax from a container 38 disposed above the plate 35 in a member 39 which is connected by screws 55 with the casing 33 it being noted that the bottom member 31 is connected to the casing 33 in a similar manner. The member 39 is provided with a central opening 390 which receives the neck portion 380 of the container 38. A regulating valve 41 extends above a valve seat 42 at the upper end of the neck portion 380 and the flow of wax from the vessel 38 can be controlled. The wax will flow through space 44 and into the holes or openings 36. A filler cap 47 is disposed on top cover 48. The plate 35 is shaped to have portions high at the center of the same and sloping to the side so that a portion of the wax will flow laterally before passing through small central openings 36.

On the face of the attachment 25 is a bracket 51 in which a handle socket 52 may be adjusted and retained by a clamping member 53 in its adjusted position. When the attachment 24 is to be used independently of the brush or broom the handle 17 of the broom or brush is connected to the attachment through the medium of the bracket 52, as shown in Figure 9.

In operation the brush can be used alone as illustrated in Fig. 8 free of the polisher attachment or the polisher attachment can be used free of the broom. If desired, the polisher attachment 25 is connected to the broom through the member 23 and a bracket portion extending upwardly therefrom and receiving the broom handle 17. The broom handle 17 is used when the attachment is connected to the broom. Accordingly a sweeping and polishing action can be effected simultaneously. The wax can be caused to flow in the necessary quantities to cover the floor and this wax will be spread and rubbed down by the mop 34.

While various changes may be made in the detail construction, it shall be understood that such changes shall be within the spirit and scope of the present invention as defined by the appended claim.

I claim:

A floor polishing device comprising a casing having longitudinally extending upper and lower members, provided with central openings, a plate disposed within the casing between the members, said plate having a trough extending through its longitudinal center which is provided with a series of small openings, a wax container having a neck portion receivable in the central opening of the upper member and adapted to contain wax which is to be dispensed through the opening in the upper member, a mop positioned below and in engagement with said lower member, means for securing the members and the plate to the casing, valve means carried by said container, means extending through the container to operate said valve means from the top of the container exteriorly

thereof, and said valve means coacting with the neck portion of said container to control the flow of wax from the container to the trough in the plate, a high portion in the bottom of the trough directly beneath the opening in the upper member for receiving the wax as it is dispensed through the opening whereby the wax will be caused to move laterally and downwardly toward the ends of the trough in the lower portion of the plate.
